UNITED STATES PATENT OFFICE

1,993,952

HEEL-BREAST SCOURING MACHINE

Fred Ashworth, Wenham, Mass., assignor to
United Shoe Machinery Corporation, Paterson,
N. J., a corporation of New Jersey

Application April 7, 1933, Serial No. 664,892

23 Claims. (Cl. 51—135)

This invention relates to an abrading machine and is herein illustrated as embodied in a heel-breast scouring machine of the type disclosed in United States Letters Patent No. 1,954,035, granted April 10, 1934 on my application. The machine disclosed in that patent comprises a scouring belt which is supported against the pressure of the work by a form block having a convex working surface which is substantially complementary to the heel-breast of a shoe to be operated upon. With machines of this type it is possible to present the greater portion of the heel-breast surface at once to the scouring belt. However, because the shanks of shoes are practically without exception curved transversely, there will be left on each side of the heel-breast surface adjacent to the shank a small tapering area which will not engage the scouring belt.

It is an object of the present invention to provide an improved heel-breast scouring machine of the type under consideration which will enable all portions of the heel-breast surface to be presented to the scouring belt.

The illustrated machine is provided with a pair of gage members constructed and arranged to engage the lateral edges respectively of the heel to position the heel-breast surface relatively to the scouring tool. This construction affords the advantage of enabling the gage members to engage a relatively large surface of the heel while at the same time leaving the entire heel breast free for presentation to the scouring tool. In accordance with a feature of the invention, the gages are yieldable to enable a heel to be received between them, and means are provided for preventing separation of the gage members to maintain them in gaging relation to a heel which has been inserted between them. In accordance with a further feature, the gage members are constructed and arranged not only to engage the lateral edges but also to engage the tread surface of the heel. In order to enable all portions of the heel-breast surface to be presented to the scouring belt provision is made for tilting the gages transversely of the heel. The effect of thus tilting the gages is to rock the shoe about its convexly curved shank so that there will be no portions adjacent to the shank which are not brought into engagement with the scouring belt. The gage members above referred to, by reason of the fact that they engage the tread surface of the heel, function also to determine the inclination of the heel-breast surface relatively to the scouring belt in a direction which is longitudinal and heightwise of the shoe. In the illustrated machine the

scouring tool consists of an abrading belt supported by a form block having a shape supplemental to that of the heel-breast surface, and the effect of tilting the shoe transversely would be, unless corrected, to change the angle at which the outer edge portions of the heel-breast surface engage the belt, with the result that the corners of the heel-breast would be scoured off. In order to maintain the same inclination in a direction which is longitudinal and heightwise of the shoe on all portions of the heel-breast surface, there is provided a means for tilting the gage members in a longitudinal and heightwise direction relatively to the shoe. In the illustrated machine the above-mentioned gage members are assisted in determining the longitudinal and heightwise tilting of the shoe by another gage which contacts with the forepart of the shoe. Connections are provided for coordinating the setting of this additional gage with the first-mentioned gage members as the tilting of the latter is varied to compensate for their transverse rocking movement.

The invention further consists in various features of construction and combinations of parts herein disclosed and claimed, the advantages of which will be apparent to those skilled in the art from the foregoing description, reference being made to the accompanying drawings, in which

Fig. 1 is a view in side elevation of a machine embodying the invention;

Fig. 2 is a plan view of the machine on a larger scale;

Fig. 3 is a view in side elevation showing a portion of the machine on a still larger scale;

Fig. 4 is a front elevation of the portion shown in Fig. 3;

Figs. 5 and 6 are enlarged views in front elevation showing portions of mechanism of the machine;

Figs. 7 and 8 are detail views illustrating the operation of the machine upon a shoe;

Fig. 9 is a perspective view showing a detail of the mechanism; and

Fig. 10 is a cross-sectional view in elevation taken on the line X—X of Fig. 2.

The supporting structure of the machine consists of a standard 10 provided with a base 12 and carrying at its upper portion a hollow frame 14. Access to the interior of the frame 14 is provided by a pair of hinged cover-plates 16 and 18, respectively. The frame 14 constitutes a housing for an abrasive belt 20 which passes over a drive-pulley 22, a pair of idler pulleys 24 and 26, respectively, and a form block 28. The drive-

pulley 22 is fixed upon the upper end of a shaft 30 of a motor 32 carried by a bracket 34 which is supported by the standard 10. The upper end of the shaft 30 extends into the frame 14 which 5 houses the drive-pulley 22. The drive of the motor 32 is controlled from a switch-box 36 positioned upon the forward end of the frame 14 and connected to the motor 32 by a conduit 38. An exhaust blower casing 40, also supported by the 10 bracket 34, is positioned below the motor 32. A rotary blower member within the casing 40 is driven by the lower end of the shaft 30. Connecting the suction end of the blower 40 to a horizontal duct 41 formed in the interior of the 15 frame 14 (Fig. 2) is a conduit 42. The dust which arises from the abrading action of the belt 20, and which is released adjacent to the forward end of the duct 41 will be conducted through the duct 41 and the conduit 42, and will thence be 20 discharged through the exhaust end of the blower casing 40 into a dust-collecting conduit.

The idler pulley 24 is journaled in a bracket 44 mounted on the housing 14. The idler pulley 26 is journaled in a bracket 46 which is in the form 25 of a bell-crank pivotally mounted in the housing 14 upon a fulcrum pin 48. An arm 50 of the bell-crank 46 carries an upstanding pin 52 which enters a groove 54 in a horizontally disposed screw 56 which is threaded in a boss 58 formed 30 in a side wall of the housing 14. The adjusting screw 56 is operated by a hand wheel 60 through a clutch 62 comprising a pair of members having interengaging teeth which are so inclined as to slip when resistance is encountered in tightening 35 the adjusting screw 56. A spring 64 maintains the clutch members 62 yieldingly in operative engagement. The turning of the adjusting screw 56 to move the arm 50 in a counterclockwise direction, as viewed in Fig. 2, serves to move the pulley 40 26 in a direction to increase the tension of the belt 20, the extent, however, to which the belt 20 may thus be tensioned being limited by the slipping of the clutch members 62.

The forward end portion of the frame 14 is recessed, as indicated at 65 to enable the heel-breast surface of a shoe to be presented to the abrasive belt 20. The recess 65 provides room for the toe end of the shoe. The cover-plate 18 is similarly recessed. The form block 28 is carried by a 50 bracket 66 which has an upstanding flange 67 which is slidable in a vertical guideway formed in an upstanding flange 69 of a bridge 68 integral with the frame 14 and extending across the recess 65. The bracket 66 may be clamped in any 55 desired position of vertical adjustment by a screw 70. The form block 28 is slidably mounted for adjustment forwardly and rearwardly in the bracket 66 and is clamped in any desired position of such adjustment by a screw 72. The form 60 block 28 has a convex operative face which is shaped to a curvature complementary to that of the desired contour of the breast surface of the heel to be scoured, and it provides backing for the scouring belt 20, causing the scouring belt to 65 assume the desired shape. The form block is readily removable and replaceable, and several form blocks of different degrees of convexity respectively may be provided to accommodate the various shapes of heel-breast surfaces on different styles of shoes. A guide 75 on the form 70 block 28 engages the upper edge of the belt and keeps the belt from riding up upon the form block. Many of the parts of the machine so far described are similar to corresponding parts of 75 the machine disclosed in my above-mentioned

Letters Patent No. 1,954,035. The form block of the present illustrated machine, however, is of wood rather than metal.

The breast surface of a heel of a shoe to be operated upon by the machine is presented to the abrading belt 20 in the position shown in Fig. 8. The heightwise position of the shoe is determined by a gage 73 secured against the under surface of the form block 28. As shown in Fig. 8, the under surface of the form block 28 is beveled to avoid interference with the shoe and to enable the shoe to be presented in any desired position of longitudinal heightwise inclination.

For positioning the breast surface of the heel of a shoe in a desired angular relation to the operative portion of the abrading belt 20, there are provided a pair of gage members 74. These gage members, as shown in Figs. 4, 5 and 10, are angular in form, each having a flange 76 for engaging a heel bottom and a flange 78 for 20 engaging a lateral edge of the heel. Each of the 25 gage members 74 is pivotally mounted upon a pin 80 having a substantially vertical axis and secured in a bracket 82 carried at the lower end of a depending lever 84. A spring 86 surrounding the pin 80 serves normally to maintain the gage members 70 in inclined relation to each other with their rear ends closer together than their forward ends to facilitate the introduction of a heel. As the heel is inserted between the two 30 gage members, the springs 86 yield and enable the gage members to assume a substantially parallel relation to each other. As previously 35 stated, there is provided for each of the gage members 74 a supporting lever 84. Each of the 40 levers 84 is pivotally mounted upon a pin 88 and the pins 88 are secured in a bracket 90. Each of the arms 84 has a substantially horizontal bell-crank extension 92 terminating in a gear sector, and these two gear sectors intermesh so that the movement of either of the levers 84 about its 45 pivot 88 will cause a like movement on the part of the other lever 84, thereby coordinating the positions of the gage members 74 with respect to a common fixed center line. The two levers 45 are connected by a tension spring 94 which urges them together. In order to provide for adjustment of the inclination of the gage member 74 in a direction which is longitudinal and heightwise 50 relatively to the shoe, the brackets 82 are pivotally mounted upon the levers 84, respectively, by means of pins 98 (Fig. 3). Each of the brackets 82 has a forwardly extending portion 100 which serves as a crank arm. Pivotally connected to the forward end of each of the cranks 100, is an 55 adjusting rod 102. To accommodate the rotary movements of the cranks 100, the lower ends of the rods 102 are slotted, being formed as hooks for convenience in assembling. Each of the rods 102 is guided in the lever 84 which carries 60 the bracket 82 to which the rod 102 is connected. Each of the rods 102 at its upper end carries a pair of spaced collars 104 (Fig. 6). Between the collars 104 on each of the rods 102 is a knob 106 which constitutes one end of the lever 108. The 65 levers 108 are pivoted upon the pins 88, respectively. The opposite ends of the levers 108 constitute gear sectors that intermesh with each other so that the up-and-down movement of either of the rods 102 will be transmitted to the 70 other rod 102 through the levers 108 and the gear sectors, which serve to coordinate the up-and-down adjustments of the gage members 74. One of the rods 102 is threaded in a pin 115 75 journaled between a pair of ears 110 formed in

- one of the levers 84 so that the turning of the rod 102, by means of a knurled head 112, will effect the simultaneous adjustment of both of the gage members 74. For the purpose of limiting the inward movements of the gage members 74 under the influence of the spring 94, there is provided a stop-screw 114 which engages the bell-crank arms 92 and which is threaded in a bracket 116 mounted upon the bracket 90.
10. The bracket 90 is carried by a bracket 184. Provision for up-and-down movement of the bracket 90 relatively to the bracket 184 is provided by means later to be described. The bracket 184 is pivotally mounted upon a pin 118 for the purpose of enabling the depending arms 84 and the gages 74 to be swung up out of the way when it is desired to remove or replace the bearing block 28 or whenever access to this portion of the machine is required for any other reason. The pin 118 is mounted in a rotary sector 120 and the bracket 184 is locked in either of its two positions; that is, either its down and operative or its up and out-of-the-way position in relation to the sector 120, by means of a spring-pressed pin 122 which engages one or the other of two notches 124 formed in the curved surface of a latch member 126 secured upon the sector 120. A pair of lugs 125 (Fig. 4) extending from the sector 120 are engageable respectively with a pair of lugs 127 (Fig. 3) extending respectively from the levers 84 to afford support and backing for the levers 84 when the latter are down in operative position. The sector 120 is guided for rotary movement by a pair of slotted sectors 128 and 130, respectively. The slotted sector 128 is supported by a trunnion pin 129 (Fig. 3) mounted in a bracket 132 which is secured upon the forward portion of the frame 14 adjacent to one side of the bearing block 28.
30. The slotted sector 130 is likewise supported by a trunnion pin 131 (Fig. 10) mounted in a bracket 134 which is secured to the frame 14 adjacent to the opposite side of the bearing block 28. The trunnion pins 129 and 131 are coaxial and they provide for tilting movement of the sector 120 in a direction which is heightwise and longitudinal relatively to the machine. The axis of rotation of the sector 120 in the guides 128 and 130 intersects the axis of the trunnions 129 and 131 and is perpendicular thereto at the longitudinal center line of the machine. The gage members 74 are thus capable of a universal tilting movement about the intersection of these two axes.
35. Rotary movement of the sector 120 in its slotted guideways is effected by a treadle 136 fulcrumed at 138 in the base of the machine and connected by a rod 140 which extends upwardly through the standard 10 to a lever 150 fulcrumed upon a pin 152 carried within the upper portion of the standard 10. The treadle 136 is normally held up by a spring 137. Upon the free end of the lever 150 is formed a gear sector 154 (Figs. 2 and 4). Meshing with the sector 154 is a pinion 156 carried upon the end of a shaft 158, the forward end 40 of which is journaled in a depending portion 160 of the bracket 134 and the rear portion of which is journaled in a bearing 162 formed in a bracket carried by the standard 10. Secured upon the forward end of the shaft 158 is a crank 164 having formed in it a slot 166 within which is slidably mounted a block 168 (Fig. 3). Pivotally mounted upon a pin 169 extending from the block 168 is a collar 171 having a pair of spaced ears which carry a pin 173. One end of a connecting rod 75 170 is pivoted upon the pin 173. The opposite end of the connecting rod 170 is pivotally connected to a pin 172 which extends through and is rotatable in the rotary sector 120. The above-described connections between the connecting rod 170 on the one hand and the block 168 and the sector 120 on the other hand constitute in effect universal joints which accommodate the sector 120 not only in its rotary movement in the guideways 128 and 130, but also in its tilting movement about the trunnions 129 and 131. The guideway 10 5 130 is slotted for movement of the pin 172. The block 168 may be clamped in any desired position of adjustment in the slide 166 by means of a clamping screw 174 which is threaded upon the pin 169 and which serves to adjust the effective throw of the crank 164 and thereby to determine the extent of movement of the sector 120 for a complete turn of the shaft 158. It is desirable in each operation to effect one complete rotation of the shaft 158, and the gear sector 154 and the pinion 156 are so designed that a complete depression of the treadle 136 will effect a complete rotation of the shaft 158. In order to avoid undesired reverse movement of the sector 120 as the treadle is returned to its normal position by the spring 137 or in case the operator should inadvertently release his pressure on the treadle 136 before completing the operation, the pinion 156 is connected to the shaft 158 by means of a pawl 176 which engages a ratchet formed in the pinion 156 so that rotation of the pinion 156 in one direction will be communicated to the shaft 158 but in the opposite direction will effect merely a slipping of the pawl 176 without rotating the shaft. The pawl 176 is held in engagement with the above-mentioned ratchet by means of a spring 178 surrounding the shaft 158 and retained by a collar 180 upon the end of the shaft 156.
45. As above stated, the bracket 90 is mounted for up-and-down movement relatively to the bracket 184. This is accomplished by means of a guide rod 182 which is secured to and depends from the bracket 90. Formed in the bracket 184 is a guideway 186 within which the rod 182 is slidably mounted for non-rotary reciprocation. For the purpose of holding the bracket 90 in its lowermost position, there is provided a compression spring 188 surrounding the lower portion of the rod 182 and interposed between the lower end of the guideway 186 and a collar 190 secured upon the lower end of the rod 182. It is desirable when the gage members 74 are raised into operative position to insure against any likelihood of their being separated and thereby diminishing their lateral pressure against the edges of the heel while the shoe is being manipulated. This is accomplished by providing a plunger 194 which is reciprocal within a guideway 196 formed in the slotted guide sector 128. A compression spring 198 within the guide member urges the plunger 194 laterally toward the shoe. Carried upon the end of the plunger 194 is a flat abutment plate 200 which bears against a roll 202 which is journaled in the lower end of the adjacent lever 84. It is evident that by this arrangement the pressure of the spring 198 will be transmitted by the plate 200 and roll 202 to one of the levers 84 and also through the gear sector levers 108 to the other lever 84. Ratchet teeth 204 are formed in the plunger 194 and are engaged by a pawl 206 pivotally mounted upon the slotted sector 128. The pawl 206 is normally held out of engagement with the ratchet teeth 204 by means of a lever 208 pivotally mounted at 210 upon the 50 55 60 65 70 75 80 85 90 95 100 105 110 115 120 125 130 135 140 adjacent lever 84. The lever 208 is provided with a bell-crank extension 212 which is normally engaged by a screw 214 adjustably threaded into the bracket 90. When the bracket 90 occupies its lowermost or inoperative position, the screw 214 tends to hold the lever 208 in such a position that the lower end of the lever engages a projection 216 on the pawl 206 to hold the pawl out of engagement with the ratchet teeth. Upon raising the bracket 90 the screw 214 permits the long arm 208 of the lever to drop under the influence of its own weight and this permits the pawl 206 also to drop under the influence of its own weight (aided by light spring pressure) and thereby to engage the ratchet teeth 204. The disposition of the ratchet teeth in relation to the pawl is such as to permit the spring 194 constantly to exert a closing action upon the gage members 74 but to prevent any opening movement of the gage members when they are raised to operative position.

As the gage members 74 are tilted laterally of the shoe by the sliding of the sector 120 in the slotted guide members 128 and 130, it is desirable, for reasons which later will be made apparent, to vary the tilting of the shoe in a direction which is longitudinal and heightwise relatively to the shoe. This compensatory variation is effected by tilting the guide members 128 and 130 about their trunnions 129 and 131 respectively. The axis of the trunnions 129 and 131 is positioned substantially in the plane of the lower edge of the abrading belt 20 and is substantially tangential to the curvature of the belt at the longitudinal center line of the machine, so that the heel breast of the shoe will tilt about its point of engagement with the gage 73, as shown in Fig. 8; without requiring any substantial amount of forward or rearward movement of the shoe. Such tilting is accomplished automatically by means of a cam mechanism comprising a cam roll 218 which is journaled between a pair of ears in a lug 220 which is secured to the upper portion of the sector 120. The cam roll 218 (Fig. 9) engages a cam comprising a pair of cam surfaces 224 and 226, respectively. A pair of compression springs 227, one of which is shown in Fig. 3 are employed to urge the guide members in a counterclockwise direction, as seen in that figure, to hold the roll 218 against its cam. For purposes of adjustment the two surfaces 224 and 226 are movable relatively each to the other. The cam surface 224 is formed upon a link 228 which is secured at one end by means of a pin 230 to a bar 232 and at the opposite end by means of a pin 234 to a link 236. The cam surface 226 is formed upon a link 238 which at one end is pivoted upon the pin 230 and at the other end is pivoted to a pin 240 carried by a link 242. The opposite ends of the links 236 and 242 are pivotally mounted upon a pin 244. The opposite end of the bar 232 is slotted to accommodate the pin 244 and is secured to a block 246 which is pivotally mounted for vertical swinging movement about a pin 248 carried by a bracket 250 mounted upon bracket 66. The intermediate portion also of the bar 232 is secured to the block 246 by a screw 249. Adjustment of the inclinations of the cam surfaces 224 and 226 is effected by means of a screw 252 threaded through a boss 251 formed in the bar 232 and engaging the pin 244. It is evident that adjustment of the screw 252 to move the pin 244 to the right, as viewed in Figs. 2 and 9, will serve to increase the inclination of the cam

surface and thereby to increase the compensatory tilting of the guide members 128 and 130 and thereby of the gage members 74. A reverse adjustment will serve to decrease the compensatory tilting. The block 246 is normally retained in operative position by means of a pin 254 which extends through the bracket 250 and the block 246. It is desirable to provide for readily swinging the block 246 about the pivot 248 in order to facilitate the replacement of the abrading belt. For this purpose the pin 254 is made readily removable and is provided with a knurled end 255 to facilitate withdrawal.

As has already been stated, the gage members 74 serve to determine the tilt of the shoe in a longitudinal and heightwise direction. In order to supplement this function of the gage members 74, there is provided another gage member in the form of a downwardly extending rod 256 (Fig. 3) having a ball-shaped end 258 for engagement with the bottom of the forepart of the shoe. Provision is made for a compensatory variation of the setting of the gage rod 256 to conform to the compensatory variation of tilt of the gage members 74 as the latter are tilted by the cam roll 218. The rod 256 is slidably mounted in a guideway 260 formed in the bracket 68. In threaded engagement with the rod 256 is a collar 262 carrying a pin 264 which is engaged by a slotted lever 266 fulcrumed upon a pin 268. An extension 270 of the bracket 68 supports the pin 268. The lever 266 is provided with a bell-crank arm 272 which is connected by a link 274 to an extension 276 of the slotted guide sector 128. The rod 256 is provided with a knurled head 278 to enable it to be adjusted upwardly and downwardly relatively to the block 262. Interposed between the head 278 and the block 262 is a compression spring 280 for holding the rod 256 in its adjusted position. In order to render the link 274 readily removable from its pivotal connection to the extension 276 for the purpose of enabling the abrasive belt to be removed and replaced, the end of the link 274 is hook-shaped and engages a pivot pin 282 which is normally held in locking engagement with the above-mentioned hook by means of a spring 288 but which may be pressed to the right as shown in Fig. 4 to release the hook for upward swinging movement. It is evident that the above-described arrangement insures that the gage rod 256 will be moved upwardly or downwardly as the guide sector 128 tilts about its trunnion thereby coordinating the setting of the gage rod 256 with the gage members 74 as the tilt of the latter is varied by the cam roll 218. In the operation of the machine a shoe S having a heel H is positioned by the gage mechanisms above described for presentation of the breast surface of the heel H to the abrading belt. The shoe S may be mounted upon a last L, as shown in Fig. 8. The breast line of the heel is indicated by the reference character B (Figs. 4 and 7). The operator first introduces the heel H between the gage members 74 which, as above stated, yield to permit the entrance of the heel and which exert pressure against the lateral edges of the heel by reason of the springs 94 and 198. The flanges 76, acting upon the tread surface of the heel H, function as gages to determine the angular relation of the heel-breast surface to the abrading belt 20 in a direction which is lengthwise and heightwise of the shoe. The flanges 76 are assisted in this gaging function by the gage rod 256, the ball end 258 of which engages the bottom of the

forepart of the shoe. The operator now, with the upward pressure of his hands, raises the shoe, forcing the gage members 74 upwardly against the compression of the spring 188, until the shank 5 portion of the shoe is stopped by the gage 73. The operator then presses the gaged shoe forwardly to bring the breast surface into engagement with the belt 20. Fig. 4 shows the shoe in its initial position of presentation to the abrading belt 20 without lateral tilt. It is evident that 10 in this position the greater portion of the heel-breast surface will engage the abrading belt. However, the shank of the shoe, owing to its transverse curvature as shown by the breast line B, 15 will engage the gage 73 tangentially, leaving on each side of the point of tangency a narrow tapering portion of the heel-breast surface unexposed to the action of the abrading belt. In order to 20 present these unexposed portions also to the abrading belt, the operator causes the shoe to be rocked transversely, first to one side and then to the other, by depressing the treadle 136. The position of the shoe when completely tilted to one side is shown in Fig. 7.

25 It will be remembered that the lateral pressure of the gage members 74 against the heel is derived from the springs 94 and 198. As the shoe is tilted while in the grasp of the operator, the springs 94 and 198 would tend to yield and permit the gage members 74 to separate and loosen their hold upon the shoe if it were not for the 30 above-described mechanism comprising the pawl 206. This mechanism operates automatically, as the shoe is raised, to prevent the gage members 35 from spreading.

It will be noted, when the shoe is tilted to one side, as shown in Fig. 7, that, owing to the convex curvature of the form block over which the belt 20 travels, the lateral edge of the heel-breast 40 surface will make a different angle in relation to the abrading belt 20 than the central portion of the heel-breast surface. It is for the purpose of correcting this and preventing the corners of the heel breast from being scoured off that the 45 compensatory adjustment by the cam mechanism comprising the roll 218 and the cam surfaces 224 and 226 is provided. As already described, a full depression of the treadle will effect a complete rotation of the crank 164 and thereby serve to 50 tilt the shoe first in one direction and then in the other, and finally back to its original position, whereupon the operation is complete. The shoe is then removed from the gage and the pressure upon the treadle released, leaving the gage mechanism in readiness for operation upon another 55 shoe.

Having thus described my invention, what I claim as new and desire to secure by Letters Patent of the United States is:

60 1. A heel-breast scouring machine comprising a tool adapted to scour heel breasts, a pair of gage members constructed and arranged yieldably to engage the lateral edges respectively of a heel to position the breast surface of the heel relatively to said scouring tool, and means for preventing relative separation of said gage members to maintain them in gaging relation to a heel which has been inserted between them.

65 2. A heel-breast scouring machine comprising a scouring tool, and gage means constructed and arranged to engage both lateral edges and also the tread surface of a heel to position the breast surface of the heel relatively to said scouring tool.

70 3. A machine for performing scouring opera-

tions upon shoes comprising a scouring tool, and a pair of gage members for positioning a heel of a shoe relatively to said scouring tool, one of said gage members having a pair of flanges adapted to bear against one lateral edge of the heel and against the tread surface of the heel respectively, and the other gage member having a pair of flanges adapted to bear against the opposite lateral edge of the heel and against the tread surface of the heel respectively.

5

75 4. A heel-breast scouring machine comprising a scouring tool, means for positioning a heel with its breast surface in a predetermined position relatively to said scouring tool, and a support for said positioning means constructed and arranged to enable the positioning means to be tilted transversely of the heel to present all portions of the heel-breast surface to said scouring tool.

10

80 5. A heel-breast scouring machine comprising a scouring tool, means for maintaining a heel of a shoe with the heel-breast surface in a predetermined angular position relatively to said scouring tool, and means for tilting said maintaining means transversely of the shoe to enable all portions of the heel-breast surface to be presented to the tool.

15

85 6. A heel-breast scouring machine comprising a scouring tool, a gage for positioning a shoe relatively to said scouring tool to cause the tool to operate upon a portion of the heel-breast surface at a predetermined angle to the tread surface of the heel, and means for tilting said gage to rock the shoe transversely, thereby enabling additional portions of the heel-breast surface to engage the scouring tool which additional portions 30 would otherwise, because of the transverse curvature of the shank of the shoe, be inaccessible to said scouring tool.

25

90 7. A heel-breast scouring machine comprising a scouring tool, a gage for positioning a shoe relatively to said scouring tool to cause the tool to operate upon a portion of the heel-breast surface at a predetermined angle to the tread surface of the heel, a support for said gage, said support having an arcuate slide within which the gaged shoe 45 may extend lengthwise, a guideway for said slide, and means for rocking said gage support about the center of said slide and transversely of the gaged shoe to enable additional portions of the heel-breast surface to engage said scouring tool, which 50 additional portions would otherwise, because of the transverse curvature of the shank of the shoe, be inaccessible to said scouring tool.

35

95 8. A heel-breast scouring machine comprising a scouring tool, a pair of gage members engageable respectively with the lateral edges of the heel of a shoe, each of said gage members being also engageable with the tread surface of the heel, for positioning the heel relatively to said scouring tool to cause the tool to operate upon a portion 60 of the heel-breast surface at a predetermined angle to the tread surface of the shoe, and means for tilting said gage members to rock the shoe transversely, thereby enabling additional portions 65 of the heel-breast surface to engage the scouring tool, which additional portions would otherwise, because of the transverse curvature of the shank of the shoe, be inaccessible to said scouring tool.

55

100 9. A heel-breast scouring machine comprising a scouring tool having a convex working surface 70 substantially complementary to the curvature of a heel-breast to be scoured, a gage for positioning a shoe relatively to said scouring tool to cause the tool to operate upon a portion of the heel-breast surface at a predetermined angle to the 75

tread surface of the heel, means for tilting said gage to rock the shoe transversely, thereby enabling additional portions of the heel-breast surface to engage the scouring tool, which additional portions would otherwise, because of the transverse curvature of the shank of the shoe, be inaccessible to said abrading tool, and means for tilting said gage to rock the shoe in a longitudinal and heightwise direction to compensate for the variation in said predetermined angle, which variation would otherwise result from the convexity of the working surface of said scouring tool when the shoe is rocked transversely.

10. A heel-breast scouring machine comprising a scouring tool having a convex working surface substantially complementary to the curvature of a heel breast to be scoured, a gage for positioning a shoe relatively to said scouring tool to cause the tool to operate upon a portion of the heel-breast surface at a predetermined angle to the tread surface of the heel, a support for said gage constructed and arranged for universal tilting movement of said gage, means for tilting said gage support to rock the shoe transversely, thereby enabling additional portions of the heel-breast surface to engage the scouring tool, which additional portions would otherwise, because of the transverse curvature of the shank of the shoe, be inaccessible to said scouring tool, and means 20 operated by said transverse tilting means for tilting said gage to rock the shoe in a longitudinal and heightwise direction to compensate for the variation in said predetermined angle, which variation would otherwise result from the convexity of the working surface of said scouring tool when the shoe is rocked transversely.

11. A heel-breast scouring machine comprising a scouring tool having a convex working surface substantially complementary to the curvature of a heel breast to be scoured, a gage for positioning a shoe relatively to said scouring tool to cause the tool to operate upon a portion of the heel-breast surface at a predetermined angle to the tread surface of the heel, a support for said gage constructed and arranged for universal tilting movement, means for rocking said gage support, and thereby the shoe, in a direction which is transverse relatively to the shoe to enable additional portions of the heel-breast surface to engage the scouring tool, which additional portions would otherwise, because of the transverse curvature of the shank of the shoe, be inaccessible to said scouring tool, a cam roll carried by said gage support, and a cam engageable with said roll and constructed and arranged to tilt said gage support, as the gage support is rocked transversely, in a direction which is longitudinal and heightwise relatively to the shoe to compensate for the variation in said predetermined angle, which variation would otherwise result from the convexity of the working surface of said scouring tool when the shoe is rocked transversely.

12. A heel-breast scouring machine comprising a tool adapted to scour heel breasts, a pair of gage members engageable with opposite sides respectively of a heel for positioning the breast surface of the heel relatively to said scouring tool, and means for urging said gage members yieldingly toward each other to cause them to press against the heel.

13. A heel-breast scouring machine comprising a tool adapted to scour heel breasts, a pair of gage members engageable with opposite sides respectively of a heel for positioning the breast surface of the heel relatively to said scouring

tool, means for urging said gage members toward each other to cause them to press against the heel, and means for coordinating the movements of said gage members constructed and arranged to maintain said gage members at equal distances respectively from a fixed center line.

14. A machine for performing scouring operations upon shoes comprising a scouring tool, a pair of gage members engageable with opposite sides respectively of a shoe for positioning a surface of the shoe relatively to said scouring tool, resilient means for urging said gage members toward each other to cause them to press against the shoe, and positive means for holding said gage members pressed against the shoe during manipulation of the shoe.

15. An abrading machine comprising an abrading tool, a gage for positioning a portion of a work piece in a predetermined angular relation to said abrading tool, and means for tilting said gage about an axis which is substantially perpendicular to the working surface of the abrading tool at a locality of engagement between the work piece and the abrading tool, to enable other portions of the work piece to be presented to said abrading tool.

16. An abrading machine comprising an abrading tool, a gage for positioning a portion of a work piece in a predetermined angular relation to said abrading tool, said gage being constructed and arranged for relative sliding movement of the work piece to enable the work piece to be moved into and out of engagement with said abrading tool, and means for tilting said gage to enable other portions of the work piece to be presented to said abrading tool while maintaining said predetermined angular relation between said other portions of the work piece and said abrading tool.

17. A machine for performing scouring operations upon shoes comprising a scouring tool, a pair of gage members constructed and arranged to engage the heel and the forepart respectively of a shoe to position a surface of the shoe relatively to said scouring tool, means for supporting said gage members to enable the setting of each gage member to be varied, and connecting means between said gage members constructed and arranged to coordinate the settings of said gage members.

18. A machine for performing scouring operations upon shoes comprising a scouring tool, a pair of gage members constructed and arranged to engage separate portions respectively of a shoe to position a surface of the shoe relatively to said scouring tool, and mechanism including a cam for varying simultaneously and in coordinated relation to each other the settings of said gages respectively.

19. A machine for performing scouring operations upon shoes comprising a scouring tool, a pair of gage members constructed and arranged to engage the tread surfaces of the heel and the forepart respectively of a shoe to position a surface of the shoe relatively to said scouring tool, means for varying the setting of one of said gage members, and connecting means between said gage members constructed and arranged to coordinate the setting of the other gage member with the variation effected by said varying means.

20. A heel-breast scouring machine comprising a scouring tool, a gage constructed and arranged by engagement with the heel of a shoe to determine the longitudinal heightwise inclina-

tion of the shoe, a supplemental gage engageable with the bottom of the forepart of the shoe to assist the first-mentioned gage in determining the longitudinal heightwise inclination of the shoe, means for varying the setting of one of said gages, and means for automatically coordinating the setting of the other gage with the variation effected by said varying means.

5 21. A heel-breast scouring machine comprising a driven scouring belt, a pair of gage members constructed and arranged to engage the lateral edges respectively of a heel to position the breast surface of the heel relatively to said scouring belt, and a support for said gage members constructed and arranged to enable said gage members to be moved transversely of said scouring belt from a position wherein the gaged heel is at a side of said scouring belt to a position wherein the breast surface of the gaged heel can engage said scouring belt.

10 22. A heel-breast scouring machine comprising a scouring tool, a pair of gage members con-

structed and arranged to engage the lateral edges respectively of a heel to position the heel-breast surface relatively to said scouring tool, and supporting means for said gage members constructed and arranged to enable said gage members to be moved from a position wherein the breast surface of the heel does not engage the scouring tool to a position wherein the breast surface of the heel engages the scouring tool.

5

15 23. A heel-breast scouring machine comprising a scouring tool, a pair of gage members constructed and arranged to engage the lateral edges respectively of a heel to position the breast surface of the heel relatively to said scouring tool, and a support for said gage members constructed and arranged for relative movement between said scouring tool and said gage members from a position wherein the breast surface of the gaged heel does not engage said scouring tool to a position wherein the breast surface 20 of the gaged heel engages said scouring tool.

FRED ASHWORTH.
